C. H. H.

UNITED STATES PATENT OFFICE.

OTTO LINDEMANN, OF NEW YORK, N. Y.

DESIGN FOR A BIRD-CAGE.

Specification forming part of Design No. 5,239, dated August 29, 1871.

To all whom it may concern:

Be it known that I, OTTO LINDEMANN, of the city, county, and State of New York, have invented a new and original Design for Bird-Cage; and I do hereby declare the following to be a full, clear, and exact description thereof, which will enable those skilled in the art to make and use the same, reference being had to the accompanying drawing forming part of this specification, in which drawing—

Figure 1 represents a side view of my bird-cage. Fig. 2 is a plan or top view of the same, partly in section.

Similar letters indicate corresponding parts.

My design relates to a bird-cage, which is ornamented by a string of beads or pearls which is attached to the upright wires of the cage in place of a cross-band.

In the drawing, A designates a string of beads or pearls, which I produce, by preference, out of a solid piece of metal wire by rolling or stamp-

ing, and which I term "pearl wire." The bird-cage B is constructed of upright wires *a*, which are retained in position by the cross-bands *b* and by the pearl wire A, said pearl wire being placed in a recess, *c*, formed by bending all the wires *a* outward, as shown.

By these means the pearl wire is retained in position without solder, and a bird-cage is obtained which presents a novel and ornamental appearance.

What I claim as new, and desire to secure by Letters Patent, is—

The design for a bird-cage, as shown and described.

This specification signed by me this 11th day of August, 1871.

OTTO LINDEMANN.
